UNITED STATES PATENT OFFICE.

ARGYLE CAMPBELL, OF CHICAGO, ILLINOIS, ASSIGNOR TO ENTERPRISE RAILWAY EQUIPMENT COMPANY, OF CHICAGO, ILLINOIS.

HOPPER-CAR.

1,285,031.

Specification of Letters Patent. Patented Nov. 19, 1918.

Application filed January 2, 1918. Serial No. 209,828.

To all whom it may concern:

Be it known that I, ARGYLE CAMPBELL, a citizen of the United States, residing at Chicago, in the county of Cook and State of Illinois, have invented a certain new and useful Improvement in Hopper-Cars, of which the following is a full, clear, concise, and exact description, reference being had to the accompanying drawings, forming a part of this specification.

This invention relates to improvements in hopper cars.

Objects of the invention are to provide a hopper car which has increased load carrying capacity as compared with other cars of similar type and wherein the center of weight of the load is lowered.

Other objects of the invention are to provide a hopper car of the so-called W-type having mechanism for operating the hopper doors, so arranged that the door operating mechanism is positioned beneath the hopper bottom sheets and the mechanism thereby simplified.

In the drawing forming part of this specification, Figure 1 is a part side elevation, part longitudinal section of a hopper car showing my improvements in connection therewith, the end portions of the car being broken away in order to prevent crowding of the drawing. Fig 2 is a part side elevational view, part vertical section showing more particularly the construction and arrangement of one of the hoppers together with its bucket-shaped hopper door and operating mechanism. In this figure, the full lines indicate the position of the parts when the hopper door is closed, and the dotted lines the position of the parts when the hopper door is open. Fig. 3 is a vertical, transverse, sectional view, taken substantially on the line 3—3 of Fig. 1, illustrating approximately the section for one-half only of the car. And Fig. 4 is a detailed elevational view, illustrating more particularly the location and arrangement of one of the door operating mechanisms.

In said drawing, the hopper car illustrated is of that type commonly known as the W-type of hopper car, that is, the car is provided with four hoppers, two on each side of the center sill, the hoppers being disposed in pairs on either side of the transverse center of the car and at the center of the car is formed a transversely extending

ridge, the latter comprising ridge sheets 10—10. The side walls of the car are designated by the reference 11, the center sills by 12, the hopper bottom sheets by 13, the inner longitudinally extending side hopper sheets 60 by 14 and the outer longitudinally extending side hopper sheets by 15. As clearly illustrated in Fig. 3, the inner side hopper sheets 14 are offset from the center sills 12, in order to accommodate the inner sets of hopper door hinge butts, as hereinafter described, and the outer hopper side sheets 15 are inclined inwardly toward the longitudinal axis of the car.

Each of the four hoppers of the car is provided with a scoop or bucket-shaped hopper door, designated generally by the reference A. Each of said doors A comprises a main sheet 16 bent to substantially right-angle form, as clearly illustrated in Figs. 1 and 2, 70 the upper portion 116 of said sheet being bent from the vertical where it is adapted to coöperate with the lower edge of the ridge sheet 10. The ends of the doors A are formed by two substantially triangular 75 shaped plates 17 and 18, the plates 17 and 18 being of substantially right-angle triangle form and flanged so as to overlap the edges of the main door sheet 16, as clearly indicated at 117 and 118 in Fig. 3. In this manner, the bucket-shaped doors may be made at comparatively small expense, while at the same time providing the necessary strength.

Each of the doors A is adapted to swing about an axis extending through the side 90 sheets of the corresponding hopper and at a point above the lower edge of the adjacent ridge sheet 10. To accomplish this, each hopper door A is provided at its inner side with a hinge bracket 19, which is pivotally 95 supported in the space between the center sill and hopper side sheet 14, as indicated at 20. The hinge bracket 19 may be conveniently formed of a plate of suitable shape with the edges flanged to provide the requisite strength. On the outer side, each door A is provided with another hinge bracket 21 of a shape shown in the drawing and having reinforcing flanged edges, as indicated at 121—121, said bracket being pivotally supported between the outer hopper side sheet and a depending bracket 22, as indicated at 23.

By forming the hopper doors A in the manner shown and described, I am enabled 110

to obtain the additional cubic capacity represented by the volume of the doors A, and at the same time lower the transverse ridge of the car so as to increase the load carrying capacity by the volume roughly indicated below the dot and dash line 110 shown in

Fig. 1, which represents the usual location of the transverse ridge of a car of this type.

It will also be observed that this increased capacity lowers the center of weight of the load, which is another desirable feature.

As shown in the drawing, the hopper doors A are operated in transverse pairs, each pair being connected by a transversely extending channel 24, the latter being preferably reinforced at its central portion by an angle iron 25. The operating mechanism for each pair of doors, as shown, comprises a transversely extending shaft 26 located below the corresponding hopper bottom sheets 13. At each side of the car and rigid with respect to the shaft 26, are provided lever arms 27 having forked ends 28 to which are pivotally connected bent links 29, the links 29 being pivotally connected at their lower ends by means of bolts 30 to the doors A. It will be noted that the links 29 are so bent and connected to the lever arms 27 that, when the hopper doors are in closed position, a line passing from the pivotal connection at 28 to the point of pivotal connection between the links 29 and the doors A will be slightly above the axis of the shaft 26, thus making the door operating mechanism self-locking.

At one end of each shaft 26, the latter are provided with ratchet wheels 36 with which coöperate the usual pawls 31 and cam locks 32, the bearings for the shaft 26 and support for the pawls and locks being provided by brackets 33 secured to the corresponding hopper side sheet.

As clearly shown in Figs. 1, 2 and 4, the linkages between the operating shafts and the hopper doors are extended beneath the hopper bottom sheets 13, the links 29 at their lower ends passing off to the outer side of the inwardly inclined hopper side sheets 15, as appears from Fig. 3. In order to permit this location of the operating linkages, the arrangement is made such that, to open the hopper doors, the operating shafts 26 are rotated in such a manner as to turn the lever arms 27 in a direction away from the adjacent hopper bottom sheets 13. In other words, the left hand shaft 26, as viewed in Fig. 1, is rotated in a counter-clockwise direction and the right hand shaft in a clockwise direction when opening the hopper doors.

With the arrangement of door operating mechanism above described, I am enabled to reduce the number of parts to a minimum while maintaining the self-locking feature and at the same time the arrange-

ment is unusually compact and well protected from accidental injury. As clearly appears from Figs. 3 and 4, the linkages of the door operating mechanism are disposed well within the vertical plane of the side walls of the car.

In the embodiment of my invention shown in the drawing, each pair of hopper doors is shown as operated by two sets of linkages at either side of the car, but, as will be apparent to those skilled in the art, I may employ a third set of linkages connected with the channel tie-bars at the center beneath the center sills, or each hopper door may be independently operated, the mechanism which I have shown lending itself very readily to these various conditions.

I claim:

1. In a hopper car having a central transverse ridge, and hoppers on each side thereof and on each side of the center sill, the combination with hopper doors for said hoppers, of mechanism for operating said doors, said mechanism including transversely extending shafts beneath the hopper bottom sheets, and link connections from said shafts to the doors, said link connections partly extending also directly beneath the hopper bottom sheets.

2. In a hopper car having a central transverse ridge and four hoppers, each hopper having a door opening the upper edge of which is defined by the lower edge of the adjacent transverse ridge sheet, the combination with bucket-shaped doors for said hoppers, said doors being hinged to swing about axes extending through the side sheets of the hoppers and above the upper edge of the door openings, of mechanism for operating said doors, said mechanism including transversely extending shafts located beneath the hopper bottom sheets and link connections from said shafts to the doors, said link connections being partly extended directly beneath the hopper bottom sheets.

3. In a hopper car, the combination with a hopper having a downwardly inclined hopper bottom sheet, an inner longitudinally extending side hopper sheet, a transverse ridge sheet, and a longitudinally extending outer side sheet, the latter being inclined from the side of the car toward the center thereof; of a hopper door for said hopper; and mechanism for operating said door, said mechanism including a transversely extending shaft disposed beneath the hopper bottom sheet, a lever arm on said shaft located directly vertically underneath said hopper bottom sheet, and a link connection from said lever arm to the hopper door, said link connection at that end connected to the lever arm being also disposed directly beneath said hopper bottom sheet when the door is in closed position and having its lower end extending outwardly to

- a position outside of said outer hopper side sheet.
4. In a hopper car having four hoppers arranged in pairs on opposite sides of the center sill, said car having a transverse central ridge, the combination with pivoted hopper doors for said hoppers, and mechanism for operating said doors, said mechanism including for each transverse pair of hopper doors, a transversely extending shaft disposed beneath the hopper bottom sheets, lever arms on said shaft also disposed beneath the hopper bottom sheets, and link connections from said lever arms to the hopper doors, said shaft being rotatable in a direction to swing the lever arms away from the hopper bottom sheets when the hopper doors are being opened.
5. In a hopper car having four hoppers arranged in pairs on opposite sides of the center sill, each hopper being formed by an inclined hopper bottom sheet, an inner longitudinally extending side hopper sheet spaced
- from the center sill of the car, and an outer longitudinally extending hopper side sheet, the latter being inclined from the side wall of the car toward the center sill, the combination with a bucket-shaped hopper door for each of said hoppers, means for pivotally supporting each of said hopper doors, each of said means comprising flanged plate hinge butts pivotally mounted between the inner hopper side sheet and the center sill and between the outer hopper side sheet and the side wall of the car, of mechanism for operating said doors, said mechanism including transversely extending shafts disposed beneath the hopper bottom sheets, lever arms on said shafts also disposed beneath the hopper bottom sheets, and link connections from said lever arms to the hopper doors.

In witness that I claim the foregoing I have hereunto subscribed my name this 20th day of Dec., 1917.

ARGYLE CAMPBELL.
